UNITED STATES PATENT OFFICE

2,432,282

APPARATUS FOR TREATING SHOE SOLES

William Carpenter Card, Jr., Winthrop, Mass., assignor to Compo Shoe Machinery Corporation, Boston, Mass., a corporation of Delaware

Original application March 10, 1944, Serial No. 525,911. Divided and this application February 13, 1945, Serial No. 577,652

2 Claims. (Cl. 12—1)

1

This invention relates to apparatus for use in the manufacture of footwear and more specifically to apparatus for use in the treatment of pre-cemented outsoles to facilitate the application of and the adhesive attachment of the outsoles to shoe bottoms.

More particularly the invention relates to apparatus for treating outsoles having the marginal edges of their attaching faces coated with a waterproof, thermoplastic cement, (i. e., one which does not become tacky or sticky when exposed to water at room temperature) so as to expose the outsoles prior to their being permanently secured to the lasted upper to the action of vapor such as heated water vapor simultaneously to activate the cement thereon and to mull or temper the outsole material, as more fully described in my co-pending application, Serial No. 525,911, filed in the United States Patent Office on March 10, 1944, and of which this application is a division.

A principal object of the invention is to provide suitable apparatus for carrying out the process described in my above mentioned co-pending application, or similar processes, in an efficient and economical manner.

Another object of the invention is to provide apparatus for treating cemented outsoles prior to their being permanently secured to the lasted upper, simultaneously to activate the cement thereon and to temper the outsole material, which can be utilized with available sole attaching presses to manufacture cemented shoes on a rapid and efficient production basis.

A further object of the invention is to provide apparatus which can be used to vapor treat outsoles regardless of whether they are secured or not secured at their heel ends to the heel seats of shoe uppers.

A still further object of the invention is to provide apparatus which can be used to vapor treat and maintain the contour of pre-molded outsoles or which can be used to so treat and impart a contour to unmolded outsoles prior to their being permanently secured to the lasted upper.

Other objects of the invention will in part be obvious and will in part appear hereinafter.

For a fuller understanding of the nature and objects of the invention reference should be had to the following detailed description taken in connection with the accompanying drawings, in which:

Fig. 1 is a perspective view, partly in section, showing one form of apparatus embodying fea-

2

tures of my invention and showing a plurality of outsoles in the process of treatment;

Fig. 2 is a front elevation, partly in section, of the apparatus shown in Fig. 1;

Fig. 3 is a sectional view taken substantially along lines 3—3 of Fig. 2;

Fig. 4 is a sectional view, similar to Fig. 3, but showing another form of apparatus embodying features of my invention; and,

Fig. 5 is a perspective view, partly in section, showing a further modified form of my apparatus.

Referring to the drawings and particularly to Figs. 1 to 3, there is shown a suitable and preferred form of apparatus for treating outsoles

15 with vapor, such as hot water vapor so as simultaneously to activate cement on the outsoles and to mull or temper the outsole material prior to its permanent attachment to the lasted upper. As illustrated the apparatus comprises a sole tempering and cement activating chamber generally designated 10, having a lower portion or base 11 forming a receptacle 12 adapted to hold a body 13 of liquid, e. g. water, which may be supplied from and kept at a constant level by a barometric feed tank 14. Preferably, the water in the receptacle 12 is heated by means of electrical resistance heaters 15 which may be of a known direct immersion type terminating in the form of the screw plugs 16, which are threaded into the end walls of the base 11. Of course other suitable heating means, supplying sufficient heat to bring the water to the temperature required to supply the heat and vapor necessary to mull or temper the soles and to activate the cement thereon, may be employed. Disposed above the body of water 13 at a sufficient height to prevent it from being splattered is situated a screen 17 that is located transversely of the receptacle 12 and extends longitudinally of the chamber 10; and, in the preferred form of apparatus this screen is curved to conform to the average curvature of molded outsoles so as to retain the mold in a pre-molded sole 18 or tend to mold a non-molded sole during the tempering operation to facilitate the application and leveling thereof on the shoe bottom as the sole is cement attached thereto.

Hinged to the base portion 11 at 19 is a cover member 20 which extends over the receptacle 12 and downwardly towards the angled wall 21, which serves as a shoe rest, to provide a longitudinally extending horizontal slot 22 in the front face of the tempering and activating chamber 10 and the cover is provided with a plurality of 50 dividing walls 23 which have their lower edges

curved to match the screen 17, thus forming separate compartments into which the outsoles to be treated may be inserted without interference with each other. The cover 20 also serves to retain the vapor around the outsoles during the tempering and activating operation.

In using the apparatus, the temperature of the body of water 13 in the receptacle 12 is preferably maintained at from 90°-95° C. by means of a suitable thermostatic control (not shown), and outsoles are inserted through the slots 22 into the separate compartments of the treating chamber. The outsoles are then treated by the heated water vapor for a period of up to two minutes and as each sole is removed to be placed with its lasted upper in a shoe press for permanent attachment of the sole to the upper, another untreated outsole may be placed in the vacant compartment, thus the operation of treating the outsoles may be carried along in a continuous and workmanlike manner.

The complete apparatus may be attached by the brackets 24 to or near a shoe pressing machine, e. g., as shown in the patent to Weiss, No. 1,945,762.

In the modified form of apparatus shown in Fig. 4 the cover member 20' lies adjacent and has its lower face substantially conformed to the curvature of the screen 17 so as to act positively to retain the mold in pre-molded outsoles or, in case non-molded soles are used, acts to mold them during the tempering and activating operation.

In this modified form there is also provided a perforated pipe 30 immersed in the body of water 13 through which air may be blown to agitate the liquid and to facilitate the circulation of vapor within the chamber 10'. This latter may also be used, if desired, in the form of apparatus shown in Figs. 1 and 5. By this means a lower temperature can be used in some cases when water is used as the activating and tempering liquid; or if one desires merely to activate the cement, a suitable solvent can be used in place of the water with a corresponding reduction in the temperature used, as will be well understood by one skilled in the art.

In Fig. 5 another form of apparatus is shown, in which the sole supporting member corresponding to the screen 17 in Fig. 1 is composed of spaced bars 17', which are located so as to present a flat surface to the sole. One skilled in the art will really understand that with this form of apparatus the tempering and cement activating operations can also be carried out, and the molding of the outsole can in certain cases be subsequently accomplished on the shoe press in which the cemented sole is attached in the usual manner to the shoe bottom. It will also be understood that such bars 17' may be curved and used in place of the screen 17 in the apparatus shown in Figs. 1 and 4, and that a flat screen may be used in place of the bars in Fig. 5. The two will hereinafter be referred to as a foraminous support. In each form of apparatus shown, it will be seen that when treating a sole 18 which has been previously secured to the heel portion

of the shoe bottom the front face 21 of the chamber 10 acts as a support for the lasted shoe upper 31.

In cases where outsoles are not secured to the heel seat of the shoe upper prior to being submitted to treatment by the vapor, the outsoles may be inserted into the treating chamber to allow the vapors to activate the cement thereon.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. An apparatus for activating and mulling a shoe outsole prior to its being permanently secured to a lasted shoe upper, said outsole having

its attaching margin coated with waterproof thermoplastic cement, comprising a curved foraminous supporting surface substantially corresponding to the outsole's ultimate shape on the shoe, said foraminous supporting surface being enclosed in a chamber provided with means for holding and heating liquid to form hot vapor for activating the cement and provided with means to permit the insertion of the outsole on the support, said apparatus being further provided with means for positively holding said sole against said curved foraminous support during the activating and mulling treatment.

2. An apparatus for activating and mulling a molded shoe outsole prior to its being permanently secured to a lasted shoe upper, said outsole having

its attaching margin coated with waterproof thermoplastic cement, comprising a curved foraminous supporting surface substantially corresponding to the outsole's ultimate shape on the shoe, said foraminous supporting surface being enclosed in a chamber provided with means for holding and heating liquid to form hot vapor for activating the cement and provided with means to permit the insertion of the outsole on the support, said apparatus being further provided with means for positively holding said sole against said curved foraminous support during the activating and mulling treatment.

WILLIAM CARPENTER CARD, JR.
